UNITED STATES PATENT OFFICE.

GEORGE CRISSON, OF HACKENSACK, NEW JERSEY, AND ARTHUR F. ROSE, OF WEST BRIGHTON, NEW YORK, ASSIGNEES TO AMERICAN TELEPHONE AND TELEGRAPH COMPANY, A CORPORATION OF NEW YORK.

CORD-CIRCUIT REPEATER FOR USE BETWEEN FOUR-WIRE AND TWO-WIRE CIRCUITS.

Application filed April 15, 1921. Serial No. 461,643.

To all whom it may concern:

Be it known that we, GEORGE CRISSON and ARTHUR F. ROSE, residing at Hackensack and West Brighton, in the counties of Bergen and Richmond and States of New Jersey and New York, respectively, have invented certain Improvements in Cord-Circuit Repeaters for Use Between Four-Wire and Two-Wire Circuits, of which the following is a specification.

This invention relates to transmission lines and more particularly to improved arrangements for establishing connections between two transmission lines, one or both of which are of the well known four-wire type.

It is at times desirable to utilize a two-way repeater circuit in a connection of this type. When this is the case it is necessary to provide a good impedance balance at the end of the four-wire circuit and also at the line and network terminals of the repeater in order to obtain satisfactory transmission. Ordinarily this might be accomplished by providing two special balancing networks and sets of equipment in the terminal arrangements of the four-wire circuit one to match the impedance of the circuit and one to match the impedance of the repeater. These would be of complex construction and expensive in installation. With the arrangements of this invention, however, a high degree of balance may be provided in the repeater without the use of any such special networks. There is furthermore, in accordance with the arrangements of this invention, incorporated in the circuit arrangements means whereby, when a connection of this type is completed through a cord circuit repeater, the normal circuit equivalent and repeater gain is preserved. Other features and purposes of the invention will appear more fully from the detailed description hereinafter given.

The invention may be more fully understood from the following description together with the accompanying drawing in the Figures 1 and 2 of which are illustrated a preferred embodiment of the arrangements of the invention. In Fig. 1 is shown a circuit diagram of the arrangements of the invention, while in Fig. 2 is shown a circuit diagram illustrating in schematic form the principles of operation of the invention.

The circuit of Fig. 1 shows the terminal

arrangements of a four-wire circuit, the terminal arrangements of a two-wire circuit, and a cord circuit repeater for establishing connections between said circuits. The four-wire circuit is well known in the art and might be of the type illustrated in the U. S. Patent No. 1,352,786, dated September 14, 1920, to G. A. Campbell, or other types, such as are used for transmission of carrier currents. It includes an incoming line L_1 and an outgoing line L_2 , both of which are associated with the windings of the hybrid coil 1. The windings of the hybrid coil 1 are normally connected over conductors 18 and 19 to the jack J_1 and are also connected to the usual type of balancing network N_1 . There is also provided a relay 2 whereby the windings of hybrid coil 1 may be disconnected from network N_1 and may be connected over conductors 3 and 4 to the contacts of jack J_2 . The relay 2 is controlled over conductor 5 connected to the sleeve of jack J_2 . The artificial lines 12 and 13 are also provided and may be associated with conductors 18 and 19 and 3 and 4 by the operation of the relays 14, 15, 16 and 17 for purposes which will be pointed out later.

The cord circuit repeater terminates in the twin plugs P_1 , P_2 and P_3 , P_4 , which are adapted to cooperate with the jacks J_1 , J_2 of the four-wire circuit and the jacks J_3 , J_4 of the two-wire line respectively. The contacts of plugs P_1 , P_2 are connected to the opposite sides of windings of the hybrid coil 6, while the contacts of plugs P_3 and P_4 are connected to the opposite sides of windings of the hybrid coil 9. The plugs P_1 and P_2 are commonly known as the line plugs while the plugs P_3 and P_4 are commonly known as network plugs. In the cord circuit repeater would be the repeater elements 95 10 and 11. These repeater elements might be any suitable form of one-way repeater, such for example as the well-known vacuum bulb amplifier, and are accordingly herein illustrated in schematic form only. The cord circuit repeater circuit is well known in the art and no further description thereof will be given. The two-wire line circuit L_3 terminates in the jack J_3 and there is also provided a network jack J_4 with which is associated the usual type of network N for balancing line L_3 .

When a connection is to be established

through the cord circuit repeater the plugs P_3 and P_4 are inserted in jacks J_3 and J_4 and plugs P_1 and P_2 are inserted in jacks J_1 and J_2 . The following circuit will then 5 be closed: from ground, winding of relay 2, conductor 5, sleeve contacts of jack J_2 , to plug P_2 , sleeve conductor of plug P_2 , to battery and ground. The closing of this circuit will operate relay 2 which will disconnect 10 the network N_1 from the hybrid windings 1 and connect these windings over conductors 3 and 4 to the jack J_2 and thence over conductors 7 and 8 to windings of the hybrid coil 6. This causes the cord circuit repeater 15 to act effectively as a terminal four-wire repeater. In other words it amounts to practically putting the repeaters 10 and 11 directly into the circuits L_1 and L_2 respectively by coupling the one-way circuits of the 20 four-wire line with the one-way circuits of the repeater through an intermediate four-wire circuit arrangement which includes the hybrid coil windings.

The principles of operation of the arrangements may be more clearly understood from Fig. 2 in which there is shown the circuit arrangement resulting upon the operation of relay 2. Similar reference characters have been utilized to denote like parts 25 with respect to Fig. 1. In Fig. 2 the heavy arrows show the direction the current would take when transmission takes place from circuit L_1 to circuit L_5 and the dotted arrows show the direction the current would 30 take when transmission takes place from circuit L_6 to circuit L_2 . It will be seen that current transmitted from circuit L_1 to circuit L_5 will be transmitted over a circuit including conductors 18 and 4 and one of 35 the windings of each of the hybrid coils 1 and 6 and also over conductors 19 and 3 and the remaining windings of the coils. These 40 windings in this connection act simply as transformers and the current will not affect circuits L_2 and L_6 as the conductors of 45 these circuits as connected to points of equal potential. Current transmitted from circuit L_6 to circuit L_2 will be transmitted over a balanced phantom circuit including 50 conductors 19 and 3 and windings of the coils on one side and conductors 18 and 4 and windings of the coils on the other side. Accordingly the current transmitted over 55 these phantom circuits will not affect the windings of the coils which are directly connected to circuits L_1 and L_5 and will not disturb the transmission thereover.

It is pointed out that, when a connection 60 of the above character is set up, the usual division of energy does not take place in the hybrid coils 1 and 6 since all the energy put out by one coil is transmitted to the other instead of wasting half of it in a network and all of the energy received by the 65 second coil is sent into one of the one-way

circuits of the repeater instead of being divided equally between both such circuits. This has the effect of reducing the effective transmission equivalent of the four-wire circuit by about three mile-units and also increases the repeater gain by about three mile-units, thus altering the transmission equivalent by about six mile-units from the normal. In order to compensate for this alteration and to preserve the normal transmission qualities of the circuit, when a connection of this type is set up, the artificial lines 12 and 13 and the relays 14, 15, 16 and 17 are provided. The artificial line 12 is associated with conductors 18 and 19, but is 70 normally disconnected from them and the artificial line 13 is associated with conductors 3 and 4, but is normally disconnected from them. When a circuit connection is set up through the cord circuit repeater, these 75 relays are operated over the sleeve circuits of jack J_1 and plug P_1 and the artificial lines 12 and 13 are then directly included in conductors 18, 19 and 3, 4, respectively. This 80 will compensate for any alterations in the normal transmission qualities of the circuit due to the unusual division of the energy and will cause the transmission to remain substantially constant.

While the invention has been disclosed in certain specific arrangements which are deemed desirable it is understood that it is capable of embodiment in many and widely varied forms without departing from the spirit of the invention as defined in the appended claims; for example the invention might be utilized to interconnect two four-wire circuits without the use of an intermediate repeater, or the invention might be utilized in a connection between two circuits one of which would include apparatus for sending and receiving signaling currents of carrier frequency.

What is claimed is:

1. A four-wire circuit including two one-way lines for transmission in opposite directions terminating at a station in a hybrid coil, a line jack and a network jack at said station, two of the terminals of windings of said hybrid coil being connected to said line jack and two of the terminals of said windings being connected to a balancing network, a repeater cord circuit at said station including a line plug and a network plug and a hybrid coil, two of the terminals of windings of said hybrid coil being connected to said line plug and two of the terminals of said windings being connected to said network plug, and means in said four-wire circuit operative when said line plug and network plug are inserted in said line jack and network jack respectively whereby two of the terminals of windings of said first mentioned hybrid coil may be disconnected from said balancing network 110
- 115
- 120
- 125
- 130

normally connected thereto and may be connected to said network jack.

2. A four-wire circuit including two one-way lines for transmission in opposite directions terminating at a station in a hybrid coil, a line jack and a network jack at said station, two of the terminals of windings of said hybrid coil being connected to said line jack and two of the terminals of said windings being connected to a balancing network, a repeater cord circuit at said station including a line plug and a network plug and a hybrid coil, two of the terminals of windings of said hybrid coil being connected to said line plug and two of the terminals of said windings being connected to said network plug, means in said four-wire circuit operative when said plugs are inserted in said jacks whereby two of the terminals of windings of said first mentioned hybrid coil may be disconnected from said balancing network and may be connected to said network jack, compensating artificial lines associated with said jacks, and means operative when said plugs are inserted in said jacks for connecting said compensating artificial lines in circuit with said jacks.

3. A circuit arrangement including two one-way lines for transmission in opposite directions, said two one-way lines terminating in a hybrid coil, a two-way repeater circuit, means for connecting together the

two-wire line terminals of said hybrid coil and said repeater circuit, and means for connecting together the network terminals of said hybrid coil and said repeater circuit.

4. A circuit arrangement including two one-way lines for transmission in opposite directions, said two one-way lines terminating in a hybrid coil, a two-way repeater circuit, means for connecting together the two-wire line terminals of said hybrid coil and said repeater circuit, means for connecting together the network terminals of said hybrid coil and said repeater circuit, and compensating artificial lines in each of said connecting means.

5. A circuit arrangement including two one-way lines for transmission in opposite directions, said two one-way lines terminating in a hybrid coil having line and network terminals, a second circuit arrangement including two one-way lines for transmission in opposite directions, said two one-way lines terminating in a hybrid coil having line and network terminals, and means for connecting together the line terminals of each of said hybrid coils and for connecting together the network terminals of each of said hybrid coils.

In testimony whereof, we have signed our names to this specification this 13th day of April 1921.

GEORGE CRISSON.
ARTHUR F. ROSE.
